[57] ABSTRACT

In combination with means to transport a continuous mono- or multi-filament thread in a linear thread path at a controlled rate of withdrawal, a frictional false twist device consisting of a single freely rotatable roller positioned obliquely to the linear thread path to receive a spiral loop of thread therearound, the freely rotatable roller having a concave arcuate thread contacting surface which is a surface of revolution.

FALSE TWISTING APPARATUS

This invention generally relates to a device for the frictional false-twisting of a continuous monofilament or a continuous multifilament thread or yarn of a linear high molecular weight fiber-forming polymer by looping the thread or yarn approximately once around a rotatable roller with its axis of rotation arranged obliquely to the direction in which the thread is traveling. The invention is also directed to a draw-twist or stretch-twist apparatus including the special false-twist device.

To crimp man-made monofilaments or man-made continuous multifilament yarns as defined in the German Industrial Standards, DIN 60001 (September, 1964), page 4, paragraph No. 2, it is common practice to subject them to a false-twisting treatment, i.e., to pass them over or through a heater and then through a cooling or fixing zone to a false-twisting means and finally to a take-up spool. The twist produced by the false-twisting means is carried back against the direction of thread travel through the heating means up to a twist-stopper. In this way, the largely plasticized or softened filament or multifilament thread passing the heater has the opportunity to twist and, as it passes through the cooling zone between the heater and the false-twister, the twist is fixed in it. Twisting back to the zero point, i.e., zero-twist, is achieved by the rotation of the filament or thread as it passes the twisting unit, usually by means of a so-called twist-trapper. Accordingly, the filament thus treated and then collected or wound on a take-up spool does not have a genuine twist, but merely a tendency to rotate when it is off-wound and relaxed.

Typical false-twist devices for imparting a durable torque-crimp to threads or yarns of a fibrous synthetic thermoplastic polymer are disclosed in a detailed explanation of the torque-crimp process set forth in "Woven Stretch and Textured Fabrics" by Hathorne, John Wiley & Sons (1964), Chapter 2. Attention is also directed to U.S. Pat. No. 2,803,109 for this description of the originally developed false-twist process.

In this very widely adopted texturizing process, it is further known that a continuous monofilament or continuous multifilament thread or yarn can be permitted to travel over a twisting means including a rotatable roller arranged obliquely to the direction in which the thread or yarn is traveling, cf., German Utility Model No. 1,898,540 and U.S. Pat. No. 2,946,181. The principle on which so-called "friction false-twisters" of this kind are based is that the filaments running obliquely onto the surface of the twister (which is generally positively driven although in some cases it may be freely rotatable), show a tendency to wander from their position relative to the twister, but are rolled back into their original position both by the tension inherent in the filament or thread and also by the friction between filament and twister. Known rollers for such frictional twisters are in the form of truncated cones (U.S. Pat. No. 2,946,181) or cylinders (German Utility Model No. 1,898,540). The disadvantage of cylinders is that several rollers arranged parallel to or perpendicularly of one another are usually required for guiding the filaments in a satisfactory manner. These known false-twist devices in which the monofilament or thread is looped at least partly around the twister, are unable to

operate without yarn or thread guides before and/or after the twisters. Another disadvantage of these known twisters resides in the twist slippage which occurs in contrast to more conventional false-twist spindles, e.g., small tubes equipped with a twist-trapping pin, and the false-twisting is subject to wide fluctuations. Hitherto, it has only been possible to reduce these fluctuations by arranging several rollers one behind the other.

One object of the present invention is to provide a frictional false-twist device which does not exhibit any of the disadvantages of conventional false-twisters, i.e., uncontrollable slip, the need to provide several identical rollers and/or the need for yarn guides. A further object of the invention is to provide a false-twist device which makes it possible to work at much higher take-off rates than was possible with conventional twisters of the frictional type referred to above, especially in draw-twist apparatus employing a false-twister. Take-off rates of more than 800 m/min. are now possible, being accompanied by stretching, whereas previous take-off rates were limited to about 400 m/min. Another object of the invention is to provide a false-twist device which has a sufficiently high static friction even though looping is not much in excess of 360°, i.e., using approximately one turn or spiral loop around the false-twister. These and other objects and advantages of the invention will become more apparent upon consideration of the following detailed disclosure.

It has now been found, in accordance with the invention, that especially useful and advantageous results can be achieved in a false-twist apparatus for the treatment of a continuous monofilament or multifilament thread, especially for texturizing the thread with a heat-set durable torque crimp, by employing apparatus which comprises means to transport the thread in a substantially linear path including means for withdrawing the thread from a feed source at a constant rate, and a frictional false-twist device consisting of a single freely rotatable roller arranged with its axis of rotation obliquely to the linear thread path in order to receive a single spiral loop around its circumferential surface, the roller having a concave thread contacting surface which is a surface of revolution.

The term "surface of revolution" is employed herein with its conventional meaning of a surface formed or generated by revolving a plane curve about a line in its plane, i.e., such that all cross-sections perpendicular to the axis of revolution are circles. The resulting concave thread contact surface is preferably an arcuate surface symmetrical with respect to a plane perpendicular to the axis of rotation and passing through its center, i.e., at the center of the roller axis. In other words, the roller has the same shape or configuration at each end.

In the context of this invention, a "freely rotatable" roller is one which can be easily rotated with a minimum of frictional restraint, for example by suitably mounting the roller on ball bearings, roller bearings or the like such that it can be easily turned by a filament or thread looped around the roller under tension and taken off at a constant speed, i.e., at a constant winding or withdrawal speed. In other words, the roller must be rotated by the thread without having to be positively driven by an auxiliary motor or other positive drive means.

The false-twist device employed in the apparatus of the invention consists of only a single roller because by virtue of the geometry of this roller, there is no need for one or more auxiliary rollers, thread guides or other means for improving the false-twisting action and guiding of the thread.

The term "thread contact surface" is employed herein to designate that part of the roller circumferential surface which comes into contact with the transported monofilament or continuous multifilament thread through looping approximately once around the roller. According to the invention, it is this yarn contact surface which is concave with a smooth curved or arcuate shape and represents a surface of revolution, i.e., a surface generated through revolution of a plane curve about an axis of revolution which lies in the plane of the curve as explained above.

Examples of suitable concave surfaces of revolution for the freely rotatable roller include ellipsoids, paraboloids, hyperboloids and so-called diabolos which are generated by a devil's curve.

A frictional false-twister of the invention in which the yarn contact surface of the roller is a surface of revolution generated by rotation of an arc symmetrical with respect to the centerline perpendicular of the axis of rotation of the roller, about the axis of rotation, is particularly easy to manufacture and at the same time particularly suitable for uniformly texturizing monofilaments and continuous multifilament threads or yarns.

To obtain especially uniform friction conditions between the filament or thread and the thread contact surface, it is of advantage for this contact surface to be roughened to a depth (R_s) of from about 2 to 8 microns (cf. German Industrial Standards, DIN 4762, Sheet 1). The yarn contact surface is preferably given a hard dull chrome finish for the same reasons.

The invention is also described by way of example with reference to the accompanying drawings, wherein:

FIG. 1 is a largely schematic view of draw-twist apparatus illustrating the path followed by the thread as it is looped around a twister according to the invention;

FIG. 2 is a longitudinal section through a false-twist roller according to the invention together with its mounting for free rotation on a fixed spindle.

FIGS. 3 and 4 are plan views of two differently mounted false-twist devices according to the invention in which the thread contact angle, i.e., the oblique angle between the thread and the false-twist roller is made variable by adjustably arranging and fixing the spindle in different positions.

In FIG. 1, the roller 1 acting as the false-twist device is arranged between a heated fixing pin 14 and a stretching godet 15 with its adjacent guide roller 15a of an otherwise conventional draw-twisting machine. Between the fixing pin 14 and the roller 1, there must be a sufficiently long cooling zone to ensure a heat-setting or fixing time suitable for the withdrawal rate of the false-twisted filament or thread 16. The path followed by the filament or thread extends from the delivery spool or bobbin 12, over the guide pin 13, partly around the fixing pin 14, once around the roller 1 and then with several loops around the stretching godet assembly 15 and 15a, as shown by a continuous broken line. Instead of the heated fixing pin 14, it is equally effective to install other heating devices such as

a heating plate, an elongated heating tube providing a contact and/or radiant heater or the like.

A number of variations can be made in the specific draw-twist apparatus shown in FIG. 1 provided that one retains the essential freely rotatable false-twist roller 1 with its correct position in a linear transported path between feed means and withdrawal means. For example, the supply package or bobbin 12 can be of any conventional form and one can employ a set of feed rolls to more carefully control the rate of feed as well as inserting various types of tensioning means as the thread is brought into a linear path leading to the false-twist roller. Likewise, other withdrawal means may be employed although the godet and guide roller assembly has been found to be especially advantageous. In order to achieve a uniformly false-twisted filament or thread, it is desirable to maintain a substantially constant tension and a substantially constant linear velocity of the thread as it is withdrawn in its linear path interrupted only by the loop around the false-twist roller.

It is a particular advantage of the invention that the single freely rotatable roller does not require supplemental guides, rollers, motor-driven spindles, twist-trappers or similar elements in order to function properly as a false-twist device. This means that the thread can be transported directly from the heating means or other feed point at which the backed up twist is stopped up to the false-twist roller, and likewise that the thread can then be conducted directly to the withdrawal means. The term "directly" is used here in the sense that the thread is conducted in a substantially linear free path without any contact with other threading elements such as guides, rollers or the like.

FIG. 2 provides details of one preferred embodiment of the frictional false-twist roller according to the invention. The roller 1 with its arcuate concave thread contact surface is mounted on roller bearings 7 so as to be freely rotatable on a spindle 2. A bushing 3 and rings 6 and 8 prevent the roller from being axially displaced. Discs 4 and 5 are designed to prevent dirt from getting into the bearings. The roller 1 shown in FIG. 2 has a concave yarn contact surface 9 which is in the form of a surface of revolution generated by the rotation of an arc about the axis of rotation 11, this arc which is also identified by 9 being symmetrical with respect to a perpendicular line 10 passing through the center of the axis of rotation 11 of the roller 1.

FIG. 3 illustrates a false-twist roller with a variable or adjustable contact angle. Coming from the heating plate as in FIG. 1, a thread 16 passes the roller 1 and at the same time is looped about once around it and then, while being false-twisted, continues traveling to the stretching godet and guide roller assembly. (The remaining apparatus has been omitted since it either corresponds to FIG. 1 or may include other conventional apparatus such as a take-up spool or the like.) Similarly to the arrangement shown in FIG. 2, the roller 1 is mounted for free rotation by means of roller bearings on a fixed spindle attached to an L-shaped support 17. The leg 17a of this support 17 is spaced backwardly from the roller 1 and is pivotally mounted for rotation to a supporting plate or frame 19 at the center of rotation 18 by means of a suitable locking screw. At the free end of the roller support 17, there are reference marks 21 which indicates the thread

delivery or contact angle on a scale 20. The contact angle is that angle between the thread delivery direction and the central line 10 perpendicular to the roller axis 11.

The false-twist roller shown in FIG. 4 largely corresponds to that shown in FIG. 3, except that the pivotable roller support 17' differs somewhat in design so that its fastening to the supporting frame 19' is also slightly different. Where the front edge 22 of the frame 19' corresponds to the linear direction of thread delivery, the angle of contact can be easily measured with a conventional protractor or other tool.

The device according to the invention is particularly suitable for texturizing monofilaments and continuous threads having only two or three individual filaments. Polyamide threads, i.e., nylon threads, having a denier or size of dtex 14 f 2, dtex 22 f 1, dtex 22 f 2 and dtex 22 f 3, have been successfully false-twisted and tests with deniers of dtex 50 have also been successfully conducted as have tests with other fibrous polymers, for example polyesters such as polyethylene terephthalate. (The total yarn size is measured as "dtex" preceding the value given while *f* precedes the number of individual filaments in the thread.)

The false-twist roller of the invention in combination with other conventional thread transporting apparatus and especially in a so-called draw-twist or stretch-twist machine permits very high speed operation with a corresponding improvement in production capacity. The false-twist roller itself is light in weight and easily constructed so that it will rotate freely at high speeds in frictional contact with the running thread. With a relatively long free path of the thread both before and after the false-twist roller, there are no other parts or thread contacting elements which can interfere with the smooth and trouble-free operation of the single roller. Moreover, the rotational velocity of the roller according to the invention is self-regulating and there is a minimum of thread slippage or loss of twisting so that very uniformly texturized filaments or threads can be obtained when processing preferred synthetic thermoplastic fibrous polymer filaments in an otherwise conventional manner.

The invention is hereby claimed as follows:

1. False-twist apparatus for the treatment of a continuous monofilament or multifilament thread composed of a linear fibrous high molecular weight polymer, which apparatus comprises:

means to transport said thread in a substantially

linear path including means to withdraw said thread from a feed source at a controlled rate; and a frictional false-twist device consisting of a single freely rotatable roller arranged with its axis of rotation obliquely to said linear thread path in order to receive said thread in a single spiral loop therearound, said freely rotatable roller having a concave thread contact surface which is a surface of revolution.

2. False-twist apparatus as claimed in claim 1 wherein said concave thread contact surface of said freely rotatable roller is an arcuate surface symmetrical with respect to a plane perpendicular to the roller axis of rotation at the center of said roller axis.

3. False-twist apparatus as claimed in claim 1 wherein the thread contact surface is roughened to a depth of about 2 to 8 microns.

4. False-twist apparatus as claimed in claim 1 wherein said thread contact surface has a hard dull chrome finish.

5. False-twist apparatus as claimed in claim 2 wherein the thread contact surface is roughened to a depth of about 2 to 8 microns and has a hard dull chrome finish.

6. False-twist apparatus as claimed in claim 1 wherein said thread withdrawal means is a stretching godet and guide roller assembly arranged to receive said thread directly from said freely rotatable roller.

7. False-twist apparatus as claimed in claim 1 including heating means for heating said thread as it is transported in said linear thread path leading up to said freely rotatable roller, said heating means being separated from said freely rotatable roller by a distance sufficient to permit cooling of the thread and fixation of the twist imparted thereto.

8. False-twist apparatus as claimed in claim 7 wherein said heating means is a heated pin at the beginning of said linear thread path leading up to said freely rotatable roller.

9. False-twist apparatus as claimed in claim 7 wherein said heating means is arranged to transport the thread directly therefrom in said linear path to said freely rotatable roller and said thread withdrawal means is arranged to receive said thread directly in said linear path from said freely rotatable roller.

10. False-twist apparatus as claimed in claim 9 wherein said thread withdrawal means is a stretching godet and guide roller assembly.
